(57) **CLAIM**

The ornamental design for a polygonal speaker housing with lid, as shown and described.

DESCRIPTION

FIG. 1 is a front and right perspective view of a polygonal speaker housing with lid showing my new design;

FIG. 2 is a exploded perspective view thereof;

FIG. 3 is an enlarged top plan view thereof;

FIG. 4 is a front elevational view thereof;

FIG. 5 is a side elevational view thereof, the other sides not shown being identical thereto;

FIG. 6 is a bottom plan view thereof;

FIG. 7 is a bottom plan view of the lid, shown separately for clarity of illustration;

FIG. 8 is a perspective view of a second embodiment of FIG. 1, the remaining two sides being identical to FIG. 5;

FIG. 9 is a perspective view of a third embodiment of FIG. 1 taken along the lines 9—9 on FIG. 1, the remaining two sides being identical to FIG. 1;

FIG. 10 is a front and rear elevational view of a fourth embodiment of FIG. 1, the remaining two sides being identical to FIG. 5; and,

FIG. 11 is a perspective view of a fifth embodiment of FIG. 1, the remaining two sides being identical to FIG. 9.
